UNITED STATES PATENT OFFICE.

EMERSON L. CLARK, OF LAKEWOOD, OHIO.

HEADLIGHT.

1,136,507.

Specification of Letters Patent. Patented Apr. 20, 1915.

Application filed October 16, 1914. Serial No. 866,961.

To all whom it may concern:

Be it known that I, EMERSON L. CLARK, a citizen of the United States, residing at Lakewood, in the county of Cuyahoga and State of Ohio, have invented a certain new and useful Improvement in Headlights, of which the following is a full, clear, and exact description.

The object of my invention is to secure an improved headlight for vehicles, such as automobiles, which will give an abundance of light on the road ahead, but projected in such a manner that no glare or blinding is caused to approaching drivers or pedestrians. I accomplish this result by a peculiarly designed reflector which projects the greater part of the light below the horizontal axis of the lamp and only permits the scattered light and that coming directly from the lamp, and therefore uninfluenced by the reflector, to issue into the region above the horizontal axis. This direct unreflected light can further be excluded or reduced if desired by frosting or opaqueing the portion of the globe through which it issues or by placing an obstruction in its path near the lamp where little of the light flux from the reflector will be encountered. I secure the above result by making a reflector the upper and lower half of which have the following relations:

The upper half is an approximate half paraboloid, made half by dividing a paraboloid by a plane through the axis of the paraboloid perpendicular to the plane generated by the rotation of the directrix about the axis of the paraboloid. The lower half of the reflector is similarly made from a paraboloid which may be similar or different in curvature from the paraboloid of the upper half. The lower half of the reflector is set with its focus approximately on the axis of the upper half of the reflector but in front of the focal point of said upper half. The light source which should be fairly compact according to the concentration desired is placed between these two foci. With this arrangement the light striking the upper half of the reflector will nearly all fall below the horizontal plane through the axis of the reflector and the light striking the lower half since its source is behind the focus will also be projected below said horizontal plane. Increasing the size of the light source will increase the angle of spread or diffusion of the reflected light. Increasing

the distance between the two foci above mentioned will increase the angle of depression of the light below the horizontal. It is easy by well known means to vary the distance between the two foci from the driver's seat, thus changing the distribution of the illumination.

Although I have described my invention as consisting of two separate half paraboloid reflectors, it is obvious that the same optical surfaces can be made in one piece; the lower half having its focus in front of the focus of the upper half. This latter type, however, not permitting of adjustment of the distance between the two foci.

In the drawings the figure is a diagrammatic representation of a vertical section through the axis of the reflector.

A is the section of the upper reflecting surface, B is the section of the lower reflecting surface, K is the axis of the two reflecting surfaces.

C is the focus or region of concentration for axially parallel light on the reflector A; D is the corresponding point of reflector B.

F represents the light source between C and D.

P is any point on the reflecting surface A, Q any point on the reflecting surface B.

CPM is a path of light issuing from the focus C and striking P. It is to be noted that PM is approximately parallel to the axis K.

FPH is the path of a bundle of light rays from the source F striking P. It is to be noted that PH diverges from PM toward the axis K.

DQO is a path of light issuing from the focus D and striking reflector B at Q. It is to be noted that QO is approximately parallel to the axis K.

FQJ is the path of a bundle of light rays issuing from the source F. It is to be noted that the rays QJ diverge from QO away from the axis K. It is thus possible by surrounding a light source F with the half paraboloids represented by A and B placed with their foci as shown, to throw all of the reflected light to one side of the axis, which result is desired for reasons above stated.

Having now described my invention, what I claim as new and wish to protect by Letters Patent is:

1. In a headlight the combination of two reflecting surfaces consisting of approximate half paraboloids of revolution set with their

axes approximately coincident but with the focus of one in advance of the focus of the other.

2. In a headlight the combination of two reflecting surfaces, each having a region of concentration for light parallel to its axis, set with their axes approximately coincident but with the region of concentration of one set in advance of the region of concentration of the other.

3. In a headlight the combination of two reflecting surfaces, each having a region of concentration for light parallel to its axis, set with their axes approximately coincident but with the region of concentration of one set in advance of the region of concentration of the other, and a light source placed between said regions of concentration.

4. In a headlight the combination of two reflecting surfaces, each having a region of concentration for light parallel to its axis, set with their axes approximately coincident, and occupying different angular space around the axis, and with the region of concentration of one displaced along the axis with respect to the region of concentration of the other reflecting surface.

5. In a headlight, a reflector provided with two angularly displaced reflecting portions having foci which are located approximately on the axis of the reflector and are displaced one in advance of the other.

6. In a headlight, a reflector provided with

two angularly displaced reflecting portions having foci which are located approximately on the axis of the reflector and are displaced one in advance of the other, and a source of light between said foci.

7. In a headlight, a reflector having a reflection surface composed of two half sections having adjacent marginal edges approximately in a diametrical plane and the rear central portion of one being displaced axially with respect to the other.

8. In a headlight, a reflector having a reflecting surface composed of two approximate half-paraboloids occupying different angular positions and set with their axes substantially coincident, one half-paraboloid being displaced axially with respect to the other.

9. In a head-light, a reflector provided with two reflecting portions with their axes approximately coincident and one portion located above the other, each portion having a region of concentration for light parallel to its axis, the region for the upper portion being in the rear of the region for the lower portion, and a source of light between said regions.

In testimony whereof, I hereunto affix my signature in the presence of.

EMERSON L. CLARK.
